LUCKY FLAMINGO RULES

Greetings, flamingo fanciers! Welcome to the card game that celebrates the six flamingo species. Let's get started!

Object of Game: To have the lowest number of points at the end of the game, which occurs when one of the players reaches 100 points. The game is played in one or more hands, with players' points accumulating with each hand. A hand ends when one Lucky Flamingo player goes out by getting rid of all their cards, and the rest of the players add up the points of the cards left in their hands. Oh, the excitement of the Lucky Flamingo!

Game Play: One or two decks can be used. Two players are ideal, up to six can play. Choose someone from your flamingo flock to be the dealer. Deal each player eight cards (no peeking at each others cards, folks) and place the remaining cards facedown as the draw pile. The dealer will then take from the draw pile until a Flamingo Species card is drawn. This first card will be placed faceup as the discard pile and will be used by the player to the right of the dealer. Each player must discard either one or two cards upon their turn except for the last play of the hand (see Last Play of Hand). If the player does not have a card to play, they must draw until they get one.

To discard, players must place a matching Species card or any Special Party card on the discard pile. Players also have the option to draw additional cards upon their turn – for example, to try to collect a Special Party card.

Last Play of Hand: When a player is getting ready to go out, they may play the cards as usual or play one of the Last Plays below, discarding up to three cards.

- 1) One matching Species card or one Special Party card
- 2) Two or three Draw cards
- 3) Two Draw cards and one Flamingo Species card
- 4) One or two Draw cards and one Give card with or without one more card of any kind to "Give"
- 5) One or two Draw cards and one Wild card
- 6) One or no Draw card, a Wild card and a Species card
- 7) One or no Draw card, one Wild card, one Give card and the option to "Give" any other one card

Caution! You could get flamingo-slammied with a Last Play!

Flamingo Species cards (1-10): A player must be able to match either the number or the flamingo species: Greater, Andean, Chilean, James's (also known as Puma), Lesser and American (which, by the way, is also known as the Caribbean). Say hello to these little feathered friends!

Special Party cards: Draw, Wild West Guess, Take and Give cards can be played on top of any card on the discard pile.

Draw cards: When playing a Draw card, the player must discard a Flamingo Species card along with it. If the player does not have a Flamingo Species card, they must draw until they do have one. The next player to the right must draw the amount of cards shown, then play the card in the discard pile.

Wild West Guess card: The player will set one Flamingo Species card facedown in front of them and the next player must guess the flamingo species. If guessed incorrectly, the Species card is given to the next player and another Flamingo Species card from the player's hand may be discarded. If guessed correctly, the Flamingo Species card is discarded along with the Wild West card. When a player does not have a Flamingo Species card in their hand, or when guessed incorrectly and no species card, then more cards must be drawn until they get one. Facial expressions may help you guess better, so good luck with that!

Give a Flamingo card: Instructs the player to give any one card from their hand to the next player, so you may want to give them the crummiest high-numbered card you have. The player then tells the next player which Flamingo Species to play.

Take a Flamingo card: Instructs the player to take one card, without looking, from the next player's hand. The player can then look at the card and must keep it. Yeah, watch out for that slick move! The player then tells the next player which Flamingo Species to play.

Card Types	Points	Quantity of cards	
		1 deck	2 decks
Flamingo Species	face value (1-10)	60	120
Give a Flamingo	20	6	12
Take a Flamingo	20	3	6
Wild West Guess	20	4	8
Draw 1	10	7	14
Draw 3	30	4	8
Draw 7	70	2	4
Total		86	172

Alright now, players! It's Lucky Flamingo time! Will you be the Lucky Flamingo today? Be brave, alert and good luck to you all!
